UNITED STATES PATENT OFFICE

DANIEL KELLEHER, OF SANDUSKY, OHIO, ASSIGNOR TO HINDE & DAUCH PAPER COMPANY, OF SANDUSKY, OHIO.

PAPER-MAKING MACHINE.

1,179,840.

Specification of Letters Patent. Patented Apr. 18, 1916.

Application filed July 10, 1915. Serial No. 39,043.

To all whom it may concern:

Be it known that I, DANIEL KELLEHER, a citizen of the United States, residing at Sandusky, Erie county, Ohio, have invented 5 certain new and useful Improvements in Paper-Making Machines, of which the following is a specification.

This invention pertaining to paper-making machines, relates particularly to machinery for forming, directly from a pulp solution, seamless articles of paper, such as drinking cups, milk bottles, and the like.

In my invention a foraminous mold, having its interior shaped in correspondence 15 with the exterior of the article to be produced, is subjected to suction upon its exterior while the pulp solution is in its interior, the pulp solution forming a paper shell within the mold, the mold with its paper shell being later dried and the shell removed.

My improved machine contains, in its more refined form, automatic mechanism by 25 means of which the foraminous mold, while its exterior is subjected to suction, is passed through a vat containing the pulp solution and then withdrawn therefrom and carried through a heating flue which dries the paper article while in the mold, the article being 30 later discharged from the mold.

My invention will be readily understood from the following description taken in connection with the accompanying drawings in which:

Figure 1 is a side elevation of a machine exemplifying my invention, parts of the drying flue appearing in vertical section in the plane of line *b* of Fig. 2: Fig. 2 a horizontal section of the drying flue in the plane 35 of line *a* of Fig. 1: Fig. 3 a vertical section of the solution vat, with its contained mechanism, the vat appearing in vertical section in the plane of line *c* of Fig. 5, while parts 40 of the mechanism within the vat appear in vertical section in the plane of line *b* of Figs. 5, 7 and 8: Fig. 4 a rear view of the vacuum valve: Fig. 5 a vertical section of the solution vat, with its contained mechanism, in the plane of line *e* of Figs. 1, 3, 7 45 and 9: Fig. 6 a face view of the lever controlling the vacuum valve: Fig. 7 a plan of one of the mold-carriers: Fig. 8 a side view of one of the mold-carriers, portions of one 50 of the molds appearing in section in the plane of line *e* of Figs. 1, 3 and 7: Fig. 9 55 an end elevation of one of the mold carriers: Fig. 10 a vertical section of one of the pockets with a mold contained therein, the section being in the plane of line *e* of Figs. 1, 3, 7 and 9: Fig. 11 a bottom view of the 60 inner member of one of the pockets: Fig. 12 a horizontal section of the inner member of two of the pockets, in the plane of line *f* of Figs. 3, 5, 8 and 13: and Fig. 13 a vertical section of the inner member of one of the 65 pockets, the section being taken in the diametrical plane of the pocket.

A diversity of scales is employed in the drawings.

Disregarding, for the present, all consideration of the mechanism by means of which the mold is automatically inserted into and withdrawn from its vacuum pocket, and disregarding the fact that my machine embodies, in its refined form, a 70 plurality of the vacuum pockets and a plurality of the molds, I will first explain the vacuum pocket and the mold and their relation with each other, and for this purpose I direct attention, for the present, exclusively 75 to Figs. 10 to 13 inclusive.

In these figures of the drawings:—1, indicates a movable pocket-carrier provided with a circular aperture: 2, a bearing-plate secured to the exterior of the pocket-carrier: 3, a bearing-ring secured to the lower face of the bearing-plate, an annular groove being formed between the inner circular portion at the lower face of the bearing-plate and the upper face of the bearing-ring: 4, 80 a hollow shell, constituting the outer wall of the vacuum pocket, the upper end of this shell being disposed near the bearing-plate: 5, a shell disposed within shell 4 and forming the inner member of the vacuum pocket, 85 the upper ends of the inner and outer members of the vacuum pocket being secured to each other: 5^a, a vacuum chamber formed between the outer and inner shells and completely surrounding the inner shell: 6, a 90 vacuum-pipe connected with the vacuum-chamber and adapted to be connected with means for the production of a more or less perfect vacuum within the vacuum-chamber: 95 7, a narrow slot cut longitudinally 100 in shell 5 and extending from its top to its bottom so as to cause suction from the vacuum chamber to act upon the interior 105 of the mold.

2
of shell 5, along a narrow longitudinal line, this slot being cut through the shell, not in a radial direction but in a direction tangential to a circle struck from the center of shell 5, as hereinafter explained, the longitudinal direction of this slot being not parallel with the axis of shell 5 but oblique with reference to the axis, as hereinafter explained: 8, a narrow slot cut through the bottom of shell 5 and extending about half the diameter of the bottom, this slot being cut obliquely instead of squarely through the bottom, as will be later explained: 9, a circular journal-flange projecting from the upper portion of the structure forming the vacuum chamber, this flange running in the bearing formed in the groove between bearing-plate 2 and bearing-ring 3 so that the entire vacuum pocket can be freely rotated with reference to pocket-carrier 1: 10, a gasket carried by the top of bearing-plate 2 around the margin of shell 5: 11, a movable mold-carrier adapted to be brought into sealing connection with gasket 10, this mold-carrier being provided with an aperture corresponding substantially with the top of the interior shell 5: 12, a continuous wire screen, closed at its bottom and open at its top and having its upper end secured as by soldering, to a ring secured to mold carrier 11: 13, a similar wire screen but of finer mesh disposed within screen 12 and secured, along with screen 12, to the ring carried by mold-carrier 11: and 14, the ring to which the upper ends of the two screens are secured, this ring being secured to mold-carrier 11 and having a downwardly projecting tapered portion adapted to enter and fit a tapered surface in bearing-ring 2 when mold-carrier 11 is pressed into sealing engagement with the bearing-plate.

The inner screen 12 is to have its interior formed in correspondence with the interior of the paper article to be produced by the apparatus, the drawing illustrating a form suited for a drinking cup. The interior surface of this inner screen is the surface against which the paper article is to be formed and this screen may well be wire cloth of about sixty mesh. The outer screen 12 is for the purpose of reinforcing the inner screen and may well be wire cloth of about forty mesh. The slots formed in the inner member of the vacuum pocket may well be about thirty thousandths of an inch in width.

As the vacuum pocket is intended to rotate relative to the mold, there should be a sufficient degree of clearance between the exterior of the mold and the interior of the inner wall 5 of the vacuum pocket such as to prevent undesired wear of the exterior wire cloth of the mold as the vacuum pocket rotates, and this clearance should be as little as is consistent with the preservation of the

wire cloth against destructive rubbing. As the two screens are soldered to collar 14 the foraminous character of the screens ceases at substantially the top of the inner wall 5 of the vacuum pocket.

Assume, now, that the mold-carrier 11 with its mold, is dissociated from the pocket-carrier 1 and the vacuum pocket carried by it, and that the general mold structure and general pocket structure are quite out of association with any pulp solution of which the paper article is to be made. The mold-carrier 11 is now to be put into association with the pocket, the mold taking its position within the interior of the pocket in position to have the pocket rotated relative to the mold, the mold-carrier being in sealing relationship to the pocket-carrier, and held in such relationship by any suitable means, not necessary to be specified at the present stage of the explanation. The compound mold and pocket structure is now to be immersed in a pulp solution, preference being given to a bleached sulfite solution, of about the consistency used in average Fourdrinier work. Suction is now to be applied to vacuum-chamber 5^a, through the medium of vacuum-pipe 6. The result would be that partial vacuum would be produced within the trifling space around the mold, between its exterior and the inner surface of pocket-wall 5. The suction would draw water and pulp to the inner surface of the mold, the water going through the interstices of the mold and the vacuum chamber 5 and then out through vacuum-pipe 6. This would leave a coating of paper upon the inner surface of the mold, and the thickness of this coating would depend upon the length of the subjection of the pulp to the vacuum action. If the inner wall 5 of the pocket were of a general foraminous character, the paper thus formed within the mold would be of a substantially uniform thickness and character, but operation would be rather slow and uneconomical by reason of the suction acting upon the solution over too great an area to render it as effective as might be desirable. It is for this reason that I avoid giving to the inner wall of the pocket a generally foraminous character and substitute therefor the narrow slots through which the suction may take place. If the pocket remains stationary relative to the mold then the suction effect upon the mold would be upon narrow lines, almost exclusively, but the suction upon this line, substantially longitudinal, as regards the inner wall of the pocket and substantially radial as regards the bottom of the pocket, would be comparatively intense. If, now, the pocket be rotated, relative to the mold, the slots will travel in a circular path and all portions of the mold will be subjected to the intensity of the suction-effect which has

been referred to. This permits of the rapid and economical deposit upon the interior of the mold of the paper sheet and it also permits of the laying of further sheet formations within the first deposit, until the desired thickness of paper for the article is built up, all of the fibers of the paper produced within the mold being so interknit as to produce a homogeneous paper article. The arranging of the slots tangentially instead of radially, has an advantageous effect in causing the suction-action, as it travels along the surface of the screen, to exert a dragging effect upon the fibers of the pulp and to cause a more perfect interknitting of the fibers. This dragging and interknitting effect upon the pulp is enhanced by the trailing character of slots 7 and 8 and by the non-axial disposition of slot 7 and the non-radial disposition of slot 8.

When the immersion of the structure within the pulp-solution, and the rotation of the pocket relative to the mold has been carried on for such a period as will produce upon the interior of the mold such thickness of paper as is desired for the article to be produced, then the structure is to be removed from the pulp solution and the surplus solution emptied from the mold. The mold-carrier with the mold and its produced paper lining, is then to be removed from the pocket and subjected to a drying operation, as in dry or hot air. When the paper lining of the mold shall have been dried to a sufficient degree, it will have shrunken sufficiently to permit of its ready discharge from the mold by reversing the mold. The paper article is then ready for such subsequent treatment as may be desired, such, for instance, as waterproofing, or trimming, or whatever may be deemed desirable in connection with the paper article being produced. The paper article represents a seamless structure in which the fibers are thoroughly interknit, the paper article possessing the merit of superior strength and lightness and extremely low cost.

As thus far described the apparatus is assumed as having been operated by hand, a single mold being dealt with. In my refined machine, I arrange a plurality of pockets on a wheel revolved by power in the vat of pulp-solution, and I arrange a still greater plurality of molds upon an endless chain driven by power, whereby the empty molds are placed in succession within the pockets in the wheel and immersed in the solution in the vat, and the paper linings in the molds formed while the molds are in the vat, the molds being later withdrawn from the pocket-wheel and the vat and carried through a drying flue to a point for discharging the dried paper articles from the molds. I will now proceed to describe these features. However, before proceeding with

the description of other parts, I should explain, with reference to Fig. 10, that, when the mold-carrier 11 is brought into proper association with the pocket-carrier and pocket, the beveled collar 14 engaging the beveled recess in bearing-ring 2, centers the mold accurately within the pocket so that the inner wall of the pocket is free of contact with the exterior of the mold.

Proceeding with the drawings: 15, indicates a mold-carrying plate which is, in reality, the mold carrier 11 previously referred to in Fig. 10, except that it carries a plurality of the molds, two being shown in the drawings: 16, a pair of endless chains, one chain somewhat beyond each end of plate 15, there being a number of these plates connected with the chain, my practice being to connect one of the mold-carrying plates at each eighth link in the chains: 17, a plate, one attached to each chain at each eighth link thereof so that as the chains are driven forward they pull plates 17 with them, each pair of plates 17 being connected, as hereinafter described, with one of the mold-carrying plates: 18, a pair of stretcher-rods for each pair of plates 17, the construction being obviously such that each pair of plates 17 with its stretcher-rods constitutes an open frame having each end secured to one of the chains: 19, guide-ways carried by plates 17 and mold-carrying plates 15 and disposed at right angles to the general planes of mold-carrying plates 15 so that the mold-carrying plates may slide, relative to the chains, at right angles to the general plane of the mold-carrying plates: 20, a spring disposed at each end of each mold-carrying plate and coöperating between the plate and the chain-carried plates 17 and serving to draw and normally hold the mold-carrying plates and their molds in a direction outwardly away from the chains: 21, a roller mounted near each end of each mold-carrying plate 11 on the side of the plate opposite the side carrying the projecting molds: 22 (Fig. 1), a drying flue through which passes the chain with its series of mold-carrying plates: 23, an inlet for dehumidified air leading into an intermediate portion of the flue: 24, a vat to contain the pulp-solution out of which the paper articles are made, the chain being so arranged relative to the vat that, in its travel, it will carry, in succession, the mold-carriers and their molds down into and through the solution: and 25, an exemplifying height for the top of the solution in the vat.

The chains, being properly driven by power, in such manner as is to be later described, will carry each mold-plate with its molds down into the pulp-solution in the vat and then up out of the solution, the paper having been formed upon the interior of the molds while it is passing through the solution, and then through the drying flue and

then out of the drying flue to a point where the paper articles may be discharged, the empty molds being then carried again to the vat, all as will be understood from Fig. 5 1. The dehumified air may be delivered to the drying flue through the air-inlet 23, a proper deflector opposite the inlet causing the air to take the direction indicated by the arrows in Fig. 1, so that the molds with 10 their contained paper articles may pass through a considerable extent of length of the drying flue before they leave the flue. In my practice the drying flue is of considerable length, extending through several 15 stories of the mill, going vertically from near the vat and then horizontally and then vertically to a point for the discharge of the paper articles from the molds, my preference being that inlet 23 be located at a 20 point in the horizontal portion of the flue so that the proper articles are subjected to drying action in the vertical portion of the flue above the vat and in the major portion of the horizontal flue leading from such vertical portion. The chains, in their course of 25 travel, will be guided by guide pulleys or sprocket wheels, as will be later explained.

I will now explain the construction of the wheel which carries the pockets in conjunction with which the molds carried by the chains coöperate.

Proceeding with the drawings, and giving special attention to Figs. 3 and 5, incidentally referring to other figures of the drawings: 26, indicates a shaft journaled in the vat and extending across through the loops of the chains disposed within the vat: 27, a circumferential series of longitudinal passages in the shaft, one end of each passage being closed while the opposite ends open from the shaft at a point outside the vat: 28, a suction-pipe coupled to the outer end of the shaft 26 and in communication with the longitudinal passages 27, in the 30 shaft, this suction-pipe being adapted for connection with any suitable suction apparatus adapted to maintain a more or less perfect vacuum in the longitudinal passages of the shaft: 29, a swivel coupling uniting pipe 28 with the shaft, this swivel coupling being of any suitable or usual character such as is of common employment in connecting a fixed pipe with the end of a rotating conduit: 30, a pair of sprocket-wheels fast 35 on shaft 26, in line with the two chains 16, and engaging the loops of those chains within the vat: 31, a wide wheel fast on shaft 26, between the two chains 16 and carrying in its periphery a plurality of pairs of the pockets 40 4, the drawings illustrating the wheel as being provided with six pairs of these pockets, this wheel forming, in reality, the pocket-carrier 1 previously referred to, the vacuum pipes 6 of each pair of the pockets 45 being connected, by swivel couplings, with

one of the longitudinal passages 27 in the shaft, each longitudinal passage therefore communicating with a pair of the pockets: 32, guiding sprocket-wheels engaging the chains and guiding the chains in their path 70 through the vat and the drying flue, &c. and 33, gearing connecting the vacuum-pipe 6 of a given pocket with the other vacuum-pipe of the pair, in such manner that when one of the vacuum-pipes with its pocket is 75 rotated the other pocket will rotate in unison. If, now, rotary motion be given to shaft 27, by any means whatever, the chains will be caused to move through their endless paths and carry the pairs of molds in succession down into the vat and through the pulp-solution therein and then out of the vat and through the drying flue, and again to the vat. At the same time the pocket-wheel 31 upon the shaft will carry the pairs 80 of pockets in a circular path down into and through and out of the solution in the vat. And at the same time, also, there will be maintained a more or less perfect vacuum in some of the passages 27 in the shaft, and in 85 the vacuum pockets connected with such of said passages 27 as are under suction. The constructing engineer will understand that motion may be given to the chains by turning the shaft by power, or that motion may 90 be given to the shaft, and the parts carried by it, by means of power applied to the chains. My preference is to apply power to the chains in a manner to be later explained. I will now explain the means preferred 95 by me for causing the empty molds to successively enter the vacuum pockets and be sealed thereto as the molds enter the solution and be maintained in that condition until the pockets, with their contained molds, 100 leave the solution, and also the means by which suction is maintained on such of the vacuum pockets as are immersed in the solution. Continuing with the drawings, and giving 105 special consideration to Figs. 3, 4, 5 and 6: 34, indicates a pair of cams supported within the vat around the shaft in line with and adapted to have their interior functional surfaces engaged by the rollers 21 110 carried by the mold-carrying plates 15: 35, (Fig. 1) one of the paper articles which has dropped from its mold after the mold has passed through the drying flue: 36, a register-valve in the form of a disk seating 115 against the outer end of shaft 26 and centrally doweled thereto: 37, a port through this register-valve communicating with such of passages 27 in the shaft as correspond with pockets immersed in the solution in 120 the vat: 38, a universally jointed stem projecting outwardly from the register-valve and through the suction-pipe 28: 39, a spring coöoperating with the register-valve and tending to hold it tightly against the 125 130

outer end of the shaft 27, which outer end of the shaft forms the ported valve-seat for the register-valve: and 40, an adjusting lever attached to valve-stem 38 and serving as means by which the register-valve may be angularly adjusted.

Normally the molds are carried with their axes at right angles to the straight running portions of the chains, the smaller ends of 10 the molds projecting toward the inner portions of the chains. Looking at Fig. 3, the lefthand portion of the chain has brought a mold-carrier with its mold downward toward the pocket-wheel. The chains at this 15 point then bend under the appropriate ones of guide-wheels 32 and then pass around sprocket-wheels 30 carried by the shaft. The relative arrangement of parts and the timing of the motions is such that as the chains 20 take their bend as they approach the pocket-wheel a pair of the molds will be opposite a pair of pockets, and the rollers 21 pertaining to the given mold-carrier will engage the entry throat of cam 34, the result 25 being that as the chains carry the mold-carrier downward the cams cause the pair of molds to enter the appropriate pair of pockets against the resistance of springs 20 (Fig. 8). The continued action of the cams 30 causes the molds to go completely home in their pockets and causes the sealing of the molds to the bearing plates to be effected. In the seating of the molds within the 35 pockets the bevels on collars 14 (Fig. 10) brings about the accurate centering of the 40 molds within the pockets. The given molds have thus become unified with and sealed to the given pockets, bringing about the condition illustrated in Fig. 10, and this 45 condition of parts should be reached by the time the given pockets and molds have gone down into the solution in the vat. The vat should be provided with the usual appurtenances for supplying it with solution and maintaining it at a substantially constant level.

The sealed relationship between the molds and pockets is maintained by the cams, while the molds and pockets are sweeping 50 down into and through and up out of the solution. As the mold and pocket structures successively rise from the solution they reach the terminal end of the cams, and the molds withdraw from the pockets 55 and are carried up to and through the drying flue.

While the molds are passing through the solution the solution fills their interiors and suction draws the fibers toward the interior 60 of the mold and extracts water therefrom, the duration of the subjection of the molds to immersion in the solution being such that by the time the molds leave the solution there will have been formed within the 65 molds a paper of desired thickness. Suc-

tion from pipe 28 reaches all of such shaft 70 passages 27 as pertain to immersed molds, port 37 in the register valve permitting this condition to exist. Between the time when molds leave the solution and the time when molds enter the solution, the blank portion of the register valve becomes effective in closing appropriate ones of shaft 75 passages 27 so that suction is being exerted upon immersed molds only. The register valve may, by means of lever 40, be adjusted to positions of angular advance or retreat best suited for the conservation of the vacuum.

Reference will now be made to the apparatus preferred for driving the chains and pocket-wheel and for rotating the pockets while the pockets are engaged by the molds.

Proceeding with the drawings, particularly to Figs. 1, 3 and 5—41, indicates a worm-shaft: 42, a worm-gear connected with a pair of the guiding sprocket-wheels over which the chains turn: 43, a worm on the worm-shaft, this worm being in engagement with worm-gear 42: 44, a belt for giving motion to the worm: 45, a sprocket-wheel loose on shaft 27: 46, a bevel-gear loose on the shaft and fast with sprocket-wheel 45: 47, a bevel-gear fast on each of the vacuum-pipes 6 pertaining to the pockets on that side of pocket-wheel 31 which is nearest bevel-gear 46, all of the bevel-gears 47 engaging the bevel-gear 46: 48, a chain driving sprocket-wheel 45: 49, a shaft: 50, a sprocket-wheel on shaft 49 and engaged by the chain 48: and 51, a belt to give rotary motion to shaft 49.

Continuous rotary motion being given to shaft 41 causes the continuous advance of 105 the chain in such direction that the chain carries the molds in succession down into and through the solution in the vat and then up through the drying flue and thence back to the vat.

Rotary motion imparted to shaft 49 causes 110 the rotation of bevel-gear 46 and all of bevel-gears 47, and, consequently, to all of the vacuum-pockets at one side of the pocket-wheel, the gears 33, heretofore referred to, causing this series of pockets to transmit rotary motion to the series of pockets at the other side of the pocket-wheel. As the pockets at one side of the pocket-wheel turn in the direction opposite to that in 115 which the pockets at the other side of the pocket-wheel turn, the slots 7 and 8 of the two series of pockets are to be correspondingly inclined in opposite directions.

While it is obvious that the chains 16, and 125 the mechanism for rotating the pockets on their axes might be driven in constant unison, it is my preference that the chains be so driven that their speed may be independent of the speed of rotation of the pockets, and 130

such is the case in the driving system illustrated.

It is my preference that the mechanism for driving the chains and for rotating the pockets be under control as to speed, this being readily effected by any usual system of speed-changing mechanism incorporated into either or both of the drives. The speed of the chains should be such that a given mold 5 will consume such time in passing through the solution in the vat that it will accumulate upon its interior such thickness of paper as is desired for the article to be produced. This speed for the chains will be 10 dependent to some extent upon the character of the pulp-solution employed and upon the thickness desired for the paper article to be produced. The rate of accumulation of the interknitted fibers of pulp 15 upon the interior of the mold will be dependent upon the same circumstances as above noted, and also upon the efficiency of the suction action upon the exterior of the mold, and the rate of rotation of the vacuum 20 pocket relative to the advance of the mold through the solution should be adjusted accordingly.

Briefly stated, the endless chains carry a foraminous mold; the wheel carries a vacuum-pocket; the advance of the chain causes 25 the mold to be inserted into and put in sealed connection with the pocket; the combined mold and pocket passes through the pulp-solution; the movement of the combined 30 mold and pocket through the pulp-solution brings about the agitation of the pulp-solution in the vat: while so passing, the vacuum-pocket causes suction upon the exterior of the mold and draws pulp to the interior of 35 the mold, and draws water from the pulp; when the mold has passed through the solution it, with its contained paper lining, is withdrawn from its vacuum-pocket; the mold with its paper lining then goes through 40 the drying flue and becomes dried and the lining shrinks; the mold is then inverted and the paper lining drops therefrom; the empty mold is carried again to a vacuum-pocket for re-immersion in the solution.

50 It is to be understood that many of the features of construction set forth are of a merely exemplifying character, it having been my intention to set forth the principle of my invention and the best mode in which 55 I at present contemplate applying that principle.

I claim:—

1. A paper-making machine comprising, 60 an open-ended foraminous mold presenting its open end outwardly and adapted to receive a deposit of pulp upon its interior surface, a vacuum-pocket surrounding said mold, a suction connection to said vacuum-pocket to cause suction through the foraminous 65 wall of the mold, said combined mold

and vacuum-pocket being adapted for joint immersion in a body of pulp-solution, a vat adapted to contain pulp-solution in which the combined mold and vacuum pocket may be immersed, and operative 70 means for immersing the combined mold and vacuum pocket in the pulp-solution in the vat and for withdrawing it therefrom at a different point and for moving the combined mold and vacuum pocket through the pulp-solution in the vat from the point of immersion to the point of withdrawal, combined 75 substantially as set forth.

2. A paper-making machine comprising, 80 its open end outwardly and adapted to receive a deposit of pulp upon its interior surface, a vacuum-pocket surrounding said mold, the mold being separable from the vacuum pocket by direct withdrawal in an 85 axial line, operative means for inserting the mold into and withdrawing it from the vacuum pocket in an axial direction, and a suction connection to said vacuum-pocket to cause suction through the foraminous wall 90 of the mold, said combined mold and vacuum-pocket being adapted for immersion in a body of pulp-solution, combined substantially as set forth.

3. A paper-making machine comprising, 95 a mold formed of wire cloth and adapted to receive a deposit of pulp upon its interior surface, a reinforcement of coarser wire cloth closely surrounding said mold, a collar surrounding the open end of the reinforcement and mold, solder uniting the open ends of the mold and reinforcement to the collar and filling the interstices of the wire cloth where they engage the collar, and a bearing-plate adapted to receive the united 100 mold and collar and make engagement with the collar by axial motion of the mold with reference to the bearing-plate, combined substantially as set forth.

4. A paper-making machine comprising, 110 a mold formed of wire cloth and adapted to receive a deposit of pulp upon its interior surface, a reinforcement of coarser wire cloth closely surrounding said mold, a collar surrounding the open end of the reinforcement and mold and having an exterior bevel at the foot of the juncture of the collar with the reinforcement, solder uniting the open ends of the mold and reinforcement 115 to the collar and filling the interstices 120 of the wire cloth where they engage the collar, a vacuum-pocket adapted to receive said mold, and a bevel seat at the entrance to the pocket and adapted to receive the bevel of said collar and accurately position the mold 125 within the collar, combined substantially as set forth.

5. A paper-making machine comprising, 130 a foraminous mold adapted to receive a deposit of pulp upon its interior surface, a

- vacuum-pocket surrounding the mold and journaled with reference thereto so that the mold and pocket may be given rotary motion relative to each other, an inner wall for the vacuum-pocket disposed in as close relationship to the mold as is consistent with their relative rotary motion, and a narrow slot extending longitudinally of and through said inner wall, whereby a suction effect is produced upon the exterior of said mold in a circumferential progressive manner during such relative rotation of the parts, combined substantially as set forth.
6. A paper-making machine comprising, a foraminous mold adapted to receive a deposit of pulp upon its interior surface, a vacuum-pocket surrounding the mold and journaled with reference thereto so that the mold and pocket may be given rotary motion relative to each other, an inner wall for the vacuum-pocket disposed in as close relationship to the mold as is consistent with their relative rotary motion, and a narrow slot extending longitudinally of and through said wall, whereby a suction effect is produced upon the exterior of said mold in a circumferential progressive manner during such relative rotation of the parts, said slot passing through said wall in a direction tangential to a circle struck from the center of relative rotation of the parts and at such angle that the part of the slot at the exterior of the wall will be in angular advance of the part of the slot nearest the mold, combined substantially as set forth.
7. A paper-making machine comprising, a vacuum-pocket formed with an inner and an outer wall the inner wall being perforated, a foraminous mold adapted to the interior of the inner wall of the vacuum-pocket, said mold being separable from the vacuum-pocket, and means for securing the mold in sealed relationship to the vacuum-pocket, combined substantially as set forth.
8. A paper-making machine comprising, a vacuum-pocket formed with an inner and an outer wall the inner wall being perforated, a foraminous mold adapted to the interior of the inner wall of the vacuum-pocket, said mold being separable from the vacuum-pocket, means for securing the mold in sealed relationship to the vacuum-pocket, a journal-connection between the vacuum-pocket and the mold, and means for rotating both walls of the vacuum-pocket relative to the mold, combined substantially as set forth.
9. A paper-making machine comprising, a pocket-carrier, a vacuum-pocket connected with the pocket-carrier, and an annular flange projecting outwardly from the vacuum-pocket and journaled in the pocket-carrier, combined substantially as set forth.
10. A paper-making machine comprising, a pocket-carrier having an opening for the reception of a vacuum-pocket, a bearing-plate and bearing-ring secured at the margin of said opening and separated from each other to form a bearing-groove between them, a vacuum-pocket disposed within said opening, and an annular flange projecting outwardly from the vacuum-pocket and journaled in said groove, combined substantially as set forth.
11. A paper-making machine comprising, a pocket-carrier provided with an opening for the reception of a vacuum-pocket, a vacuum-pocket journaled in said opening and adapted for the reception of a foraminous mold, and a vacuum-pipe connected with the vacuum-pocket and having its axis in line with the axis of the vacuum-pocket, combined substantially as set forth.
12. A paper-making machine comprising, a foraminous mold adapted to receive a deposit of pulp upon its interior surface, a vacuum-pocket surrounding said mold and separable therefrom in an axial direction, a pocket-carrier connected with the vacuum-pocket, and a gasket carried by the pocket carrier and adapted to seal the connection between the mold and the vacuum-pocket, combined substantially as set forth.
13. A paper-making machine comprising, a vat adapted to hold a pulp-solution, a pocket-wheel journaled in said vat on a horizontal axis and adapted to dip a portion of its exterior into the solution in the vat, an outwardly open vacuum-pocket formed in said wheel, means for maintaining a vacuum in said vacuum-pocket during a part of the rotation of the wheel, a foraminous mold adapted to receive a deposit of pulp upon its interior surface and having an exterior surface adapted to the interior of the vacuum-pocket, and means for securing the mold in sealed relationship to the vacuum-pocket and for maintaining such relationship while the wheel carries the vacuum-pocket and mold into and through the pulp-solution in the vat, combined substantially as set forth.
14. A paper-making machine comprising, a vat adapted to contain a pulp-solution, a pocket-wheel journaled in said vat on a horizontal axis and adapted to dip a portion of its exterior into the solution in the vat, an outwardly open vacuum-pocket formed in said wheel, means for maintaining a vacuum in said vacuum-pocket during a part of the rotation of the wheel, an endless chain having a portion surrounding the axis of the wheel and dipping into the solution in the vat, a foraminous mold carried by said chain and having its exterior adapted to the interior of the vacuum-pocket, and means for moving the chain and pocket-wheel in unison in such manner that the mold may enter and connect with the pocket and then be carried around with the pocket.

through the solution and then out of the solution and out of the pocket, combined substantially as set forth.

15. A paper-making machine comprising, 5 a vat adapted to contain a pulp-solution, a pocket-wheel journaled in said vat on a horizontal axis and adapted to dip a portion of its exterior into the solution in the vat, an outwardly open vacuum-pocket 10 formed in said wheel, means for maintaining a vacuum in said vacuum-pocket during a part of the rotation of the wheel, a drying-flue, an endless chain having a portion surrounding the axis of the wheel and dipping into the solution in the vat and having a portion passing through said drying-flue, a 15 foraminous mold carried by said chain and having its exterior adapted to the interior of the vacuum-pocket, and means for moving the 20 chain and pocket-wheel in unison in such manner that the mold may enter and connect with the pocket and then be carried around with the pocket through the solution and then out of the solution and out of the pocket and through the drying-flue and back to the vat, combined substantially as set forth.

16. A paper-making machine comprising, 30 a vat adapted to contain a pulp-solution, a pocket-wheel journaled in said vat on a horizontal axis and adapted to dip a portion of its exterior into the solution in the vat, an outwardly open vacuum-pocket 35 formed in said wheel, means for maintaining a vacuum in said vacuum-pocket during a part of the rotation of the wheel, a drying-flue, an endless chain having a portion surrounding the axis of the wheel and dipping into the solution in the vat and having a portion passing through said drying-flue, 40 and having a horizontal portion running in a path toward the vat, a foraminous mold carried by said chain and having its exterior adapted to the interior of the vacuum-pocket, and means for moving the chain and 45 pocket-wheel in unison in such manner that the mold may enter and connect with the pocket and then be carried around with the pocket through the solution and then out of the solution and out of the pocket and through the drying-flue and back through 50 said horizontal portion on its way to the vat, whereby a paper article formed in the mold while passing through the vat and 55 dried while passing through the drying-flue may drop from the mold while passing through said horizontal path of the chain, combined substantially as set forth.

17. A paper-making machine comprising, 60 a vat adapted to contain a pulp-solution, a pocket-wheel journaled in said vat on a horizontal axis and adapted to dip a portion of its exterior into the solution in the vat, an outwardly open vacuum-pocket 65 formed in said wheel, means for maintaining a vacuum in said vacuum-pocket during 70 a part of the rotation of the wheel, an endless chain having a portion surrounding the axis of the wheel and dipping into the solution in the vat, a foraminous mold carried by 75 said chain and having its exterior adapt-

in said vacuum-pocket during a part of the rotation of the wheel, a drying-flue having a vertical portion leading upwardly from said vat and then horizontally and then downwardly, an endless chain having a portion 80 surrounding the axis of the wheel and dipping into the solution in the vat and passing through said drying-flue, a foraminous mold carried by said chain and having its exterior adapted to the interior of the vacuum-pocket, means for moving the chain and pocket-wheel in unison in such manner that the mold may enter and connect with the pocket and then be carried around with the pocket through the solution and then out of the solution and out of the pocket and through the drying-flue and back to the vat, and guide-wheels for supporting and guiding the chain in its passage, combined substantially as set forth.

18. A paper-making machine comprising, 85 a vat adapted to contain a pulp-solution, a pocket-wheel journaled in said vat on a horizontal axis and adapted to dip a portion of its exterior into the solution in the vat, an outwardly open vacuum-pocket 90 formed in said wheel, means for maintaining a vacuum in said vacuum-pocket during a part of the rotation of the wheel, an endless chain having a portion surrounding the axis of the wheel and dipping into the solution in the vat, a foraminous mold carried by said chain and having its exterior adapted to the interior of the vacuum-pocket, a mold-carrier connecting the mold with the chain, 95 guides co-operating between the chain and mold-carrier and permitting the mold to be projected inwardly of the chain, springs co-operating with the chain and mold-carrier and holding the mold in normal position out of projection inwardly of the chain, means for moving the chain and pocket-wheel in unison in such manner that the mold may enter and connect with the pocket and then be carried around with the pocket through the solution and then out of the solution and out of the pocket, and a cam disposed within the vat and adapted to engage the mold-carrier and cause the mold to move inwardly of the chain and into the pocket as 110 the pocket enters the pulp-solution, combined substantially as set forth.

19. A paper-making machine comprising, 115 a vat adapted to contain a pulp-solution, a pocket-wheel journaled in said vat on a horizontal axis and adapted to dip a portion of its exterior into the solution in the vat, an outwardly open vacuum-pocket 120 formed in said wheel, means for maintaining a vacuum in said vacuum-pocket during a part of the rotation of the wheel, an endless chain having a portion surrounding the axis of the wheel and dipping into the solution in the vat, a foraminous mold carried by said chain and having its exterior adapt-

ed to the interior of the vacuum-pocket, a mold-carrier connecting the mold with the chain, guides coöperating between the chain and mold-carrier and permitting the mold 5 to be projected inwardly of the chain, springs coöperating with the chain and mold-carrier and holding the mold in normal position out of projection inwardly of the chain, means for moving the chain and 10 pocket-wheel in unison in such manner that the mold may enter and connect with the pocket and then be carried around with the pocket through the solution and then out of the solution and out of the pocket, and a 15 cam disposed within the vat and adapted to engage the mold-carrier and cause the mold to move inwardly of the chain against the resistance of said springs and into the pocket as the pocket enters the pulp-solution 20 and permit the mold to be moved outwardly of the chain by said springs as the pocket leaves the pulp-solution, combined substantially as set forth.

20. A paper-making machine comprising, 25 a vat adapted to contain a pulp-solution, a shaft journaled in the vat on a horizontal axis and having an eccentric longitudinal passage open at one end of the shaft, a vacuum-pipe extending radially from the 30 shaft and connecting with said passage, an outwardly open vacuum-pocket carried by said pipe and adapted to be carried into and through the solution by the turning of the shaft, a suction-pipe having swiveled connection with the end of the shaft at which 35 said longitudinal passage is open, and a stationary register-valve disposed at the end of the shaft and adapted to open said longitudinal passage to said suction-pipe while the 40 pocket is passing through the solution in the vat and to close communication between said passage and the suction-pipe while the pocket is moving outside of the solution, combined substantially as set forth.

45. 21. A paper-making machine comprising, a vat adapted to contain a pulp-solution, a shaft journaled in the vat on a horizontal axis and having an eccentric longitudinal passage open at one end of the shaft, a 50 vacuum-pipe extending radially from the shaft and connecting with said passage, an outwardly open vacuum-pocket carried by said pipe and adapted to be carried into and through the solution by the turning of the 55 shaft, a suction-pipe having swiveled connection with the end of the shaft at which said longitudinal passage is open, a stationary register-valve disposed at the end of the shaft and adapted to, open said longitudinal 60 passage to said suction-pipe while the pocket is passing through the solution in the vat and to close communication between said passage and the suction-pipe while the pocket is moving outside of the solution, combined substantially as set forth.

65. 22. A paper-making machine comprising,

register-valve and holding it toward the end of the shaft, combined substantially as set forth.

22. A paper-making machine comprising, a vat adapted to contain a pulp-solution, a shaft journaled in the vat on a horizontal axis and having an eccentric longitudinal passage open at one end of the shaft, a vacuum-pipe extending radially from the shaft and connecting with said passage, an 70 outwardly open vacuum-pocket carried by said pipe and adapted to be carried into and through the solution by the turning of the shaft, a suction-pipe having swiveled connection with the end of the shaft at which 75 said longitudinal passage is open, a stationary register-valve disposed at the end of the shaft and adapted to open said longitudinal passage to said suction-pipe while the pocket is passing through the solution 80 in the vat and to close communication between said passage and the suction-pipe while the pocket is moving outside of the solution, and means for angularly adjusting the register-valve, combined substantially as 85 set forth.

23. A paper-making machine comprising, a vat adapted to contain a pulp-solution, a shaft journaled in the vat on a horizontal axis and having a circular series of longitudinal 95 passages open at one end of the shaft, vacuum-pipes extending radially from the shaft and connected each with one of said longitudinal passages, an outwardly open vacuum-pocket carried by each of said 100 vacuum-pipes and adapted to be carried into and through the solution by the turning of the shaft, a suction-pipe having swiveled connection with the end of the shaft at which 105 said longitudinal passages are open, and a stationary register-valve disposed at the end of the shaft and adapted to open said longitudinal 110 passages to said suction-pipe while the pockets communicating with the respective passages are passing through the solution in the vat and to close communication between the passages and the suction-pipe while the respective pockets are moving outside of the solution, combined substantially as set forth.

24. A paper-making machine comprising, a vat adapted to contain a pulp-solution, a shaft journaled in the vat on a horizontal axis and having a circular series of longitudinal 115 passages open at one end of the shaft, vacuum-pipes extending radially from the shaft and connected each with one of said longitudinal passages, an outwardly open vacuum-pocket carried by each of said 120 vacuum-pipes and adapted to be carried into and through the solution by the turning of the shaft, a suction-pipe having swiveled connection with the end of the shaft at which 125 said longitudinal passages are open, a stationary register-valve dis-

- posed at the end of the shaft and adapted to open said longitudinal passages to said suction-pipe while the pockets communicating with the respective passages are passing 5 through the solution in the vat and to close communication between the passages and the suction-pipe while the respective pockets are moving outside of the solution, and a swiveled connection in each of said 10 vacuum-pipes to permit of the rotation of the vacuum-pockets upon their axes while the pockets are passing through the solution, combined substantially as set forth. 15
25. A paper-making machine comprising, 15 a vat adapted to contain pulp-solution, a shaft journaled in the vat on a horizontal axis and provided with a longitudinal suction passage, means for rotating the shaft, a vacuum-pipe extending radially from the 20 shaft and connected with said longitudinal passage, an outwardly open vacuum-pocket swiveled to said vacuum-pipe and adapted to be carried into and through the solution by the turning of the shaft, and means as- 25 sociated with the vacuum-pocket and shaft to cause the vacuum-pocket to turn upon its axis while the vacuum-pocket is passing through the solution, combined substantially as set forth. 30
30. 26. A paper-making machine comprising, 30 a vat adapted to contain pulp-solution, a shaft journaled in the vat on a horizontal axis and provided with a longitudinal suction passage, means for rotating the shaft, a vacuum-pipe extending radially from the 35 shaft and connected with said longitudinal passage, an outwardly open vacuum-pocket swiveled to said vacuum-pipe and adapted to be carried into and through the solution by the turning of the shaft, and means as- 40 sociated with the vacuum-pocket and shaft to cause the vacuum-pocket to turn upon its axis while the vacuum-pocket is passing through the solution, the means for turning 45 the vacuum-pocket upon its axis being independent of the means for rotating the shaft, combined substantially as set forth. 50
27. A paper-making machine comprising, 50 a vat adapted to contain a pulp-solution, a shaft journaled therein on a horizontal axis and provided with a longitudinal suction- 55 passage, means for rotating the shaft, a plurality of vacuum-pipes extending radially from the shaft and connected with said longitudinal passage, outwardly open vacuum-pockets swiveled to said vacuum-pipes and adapted to be carried into and through and out of the solution by the turning 60 of the shaft, means for rotating one of said vacuum-pockets upon its axis, and gearing connecting the vacuum-pockets to cause their rotation in unison, combined substantially as set forth. 65
28. A paper-making machine comprising, 65 a vat adapted to contain pulp-solution, a shaft journaled in the vat on a horizontal axis and provided with a longitudinal suction-passage, means for rotating the shaft, a vacuum-pipe extending radially from the shaft and connected with said longitudinal passage, an outwardly open vacuum-pocket swiveled to said vacuum-pipe and adapted to be carried into and through the solution by the turning of the shaft, a bevel-gear connected with said vacuum-pocket, a bevel-gear loose on the shaft and engaging the bevel-gear of the pocket, and means for turning the bevel-gear on the shaft and causing the rotation of the pocket, combined substantially as set forth. 70
29. A paper-making machine comprising, 75 a vat adapted to contain pulp-solution, a shaft journaled in the vat on a horizontal axis and provided with a longitudinal suction-passage, means for rotating the shaft, a vacuum-pipe extending radially from the shaft and connected with said longitudinal passage, an outwardly open vacuum-pocket swiveled to said vacuum-pipe and adapted to be carried into and through the 80 solution by the turning of the shaft, a bevel-gear connected with said vacuum-pocket, a bevel-gear loose on the shaft and engaging the bevel-gear of the pocket, means for turning the bevel-gear on the shaft and causing the rotation of the pocket, and the means for turning the bevel-gear on the shaft being independent of the means for turning the shaft in order that the speed of rotation of the pocket upon its axis may be independent 85 of the speed of rotation of the shaft, combined substantially as set forth. 90
30. A paper-making machine comprising, 95 a vat adapted to contain pulp-solution, a shaft journaled in said vat on a horizontal axis and provided with a circular series of longitudinal passages open at one end of the shaft, a suction-pipe having swiveled connection with the shaft at the open ends of said passages, a register-valve co-operating 100 with the open end of the longitudinal passages in the shaft and adapted to leave some of the passages open and keep other of the 105 passages closed with reference to the suction-pipe, means for turning said shaft, a pocket-wheel mounted on the shaft, outwardly open vacuum-pockets carried at the periphery of the wheel with their axes radial to the shaft and arranged in circumferential and longitudinal series, vacuum-pipes connecting each of said longitudinal 110 passages with a plurality of said vacuum-pockets, swiveled couplings arranged in said vacuum-pipes to permit the pockets to rotate on their axes, gearing connecting the individual pockets of a longitudinal series, a bevel-gear connected with one of the pockets of each longitudinal series of pockets, a bevel-gear loose on the shaft and engaging the bevel-gears of the pockets, means for 115 120 125 130

driving the bevel-gear on the shaft, sprocket-wheels on the shaft at the sides of the pocket-wheel, a drying-flue extending upwardly from the vat, an inlet for drying-air into said flue, a pair of endless chains 5 engaging said sprocket-wheels and having portions passing through said drying-flue, guide-wheels engaging the chains and causing them to make their necessary turns, 10 plates carried by the chains at such intervals as to appropriately match the pockets in the pocket-wheel as the chains pass around said sprocket-wheels, guides carried by said plates at substantially right angles to the 15 chains when the chains are straight, mold-carriers engaging the guides of said plates and adapted for inward and outward move-
ment relative to the chains, springs coöperating with said plates and mold-carriers and tending to hold the mold-carriers in normal 20 outward position, foraminous molds carried by the mold carriers and adapted to enter the vacuum-pockets in the pocket-wheel and be carried in succession through the solution by the turning of the pocket-wheel, and 25 cams disposed within the vat and adapted to cause the molds to enter into and remain in connection with the pockets while the pockets are being carried through the solution, combined substantially as set forth.
